United States Patent Office

Des. 203,145
Patented Dec. 7, 1965

203,145

COSMETIC CASE

Richard H. Arbib, New York, N.Y., assignor to Bentley
Products, Inc., New York, N.Y., a corporation of New York

Filed Apr. 21, 1965, Ser. No. 84,899

Term of patent 14 years

(Cl. D87—5)

FIG. 1

FIG. 2

FIG. 5

FIG. 1 is a perspective view of a cosmetic case showing my new design in closed condition;

FIG. 2 is a perspective view thereof showing the case in open condition;

FIG. 3 is a right-side elevational view thereof;

FIG. 4 is a top plan view thereof; and

FIG. 5 is a rear elevational view thereof.

The essential features of my design are shown in full lines.

I claim:

The ornamental design for a cosmetic case, substantially as shown and described.
